Carl H. Crawford
ATTORNEY

UNITED STATES PATENT OFFICE.

LOU C. ELLER, OF SPOKANE, WASHINGTON, ASSIGNOR, BY DIRECT AND MESNE ASSIGNMENTS, TO LOCKIT CAP COMPANY, A CORPORATION OF WASHINGTON.

TANK-RISER CLOSURE.

Application filed April 11, 1927, Serial No. 182,827. Renewed October 11, 1928.

The object of this invention is to provide a novel type of closure structure for tank risers and the device of this invention is particularly designed for the risers of gasoline and radiator risers of automobiles.

A feature of the invention consists in a novel form of anchorage for the structure whereby the latter will be so effectively secured to the riser that it cannot be removed with any ordinary mechanical expedients, and in this connection, the anchorage feature involves a band structure adapted to outwardly engage the riser.

A feature of special novelty resides in a form of locking screw head which, after being turned home into a final locking position, cannot be released with the same implement that was employed to turn it home.

A further feature resides in a spring which normally acts to seat the closure so as always to insure coverage of the riser against the entrance of foreign matter thereto, and in this connection, it is a further feature to employ a locking device that will automatically function to lock the closure seated when the spring has forced the closure into a closing position.

The invention has many other objects and features that will be more fully described in connection with the accompanying drawing and which will be more particularly pointed out in and by the appended claims.

In the drawings:

Fig. 1, is a view in side elevation showing the most improved form of my invention.

Fig. 2, is a sectional view on line 2-2 of Fig. 4, with the closure seated.

Fig. 3, is a sectional view on line 3-3 of Fig. 2.

Fig. 4, is a plan view of the device.

Fig. 5, is a sectional view on line 5-5 of Fig. 2.

Fig. 6, is a view in elevation of my improved locking screw.

Fig. 7, is another view thereof.

Fig. 8, is a top plan view thereof.

Like characters of reference designate similar parts throughout the different figures of the drawing.

As shown, a riser is indicated at 1 and the same has an inturned flange 2, the crown of which acts as a seat for the closure. The periphery of the riser is usually threaded to a certain depth but the device of my invention is not dependent upon a threaded

connection as it is arranged and constructed to coact either with a threaded or smooth exterior surface.

I will first describe my novel form of band anchorage before proceeding with a description of the cap or closure structure.

This portion of the device involves what I will term an adapter anchoring band 3, which as shown, is a continuous annular strip and is so equipped that it can be adapted to a wide range of risers irrespective of threaded or smooth surfaces and irrespective of variations and irregularities in diameters, within reasonable ranges. This band, 3, fits over the riser 1, as shown, near the top of the latter, and is provided with an annular bead 4, adapted to receive the flanges of those types of risers which are turned outwardly instead of inwardly. It also functions to strengthen the band 3. The band 3, is provided with an offset portion 5, into which the annular bead 4 merges, and transversely of the band, or in its normal position, vertically thereof, said offset portion is suitably tapered as shown in Fig. 2, the upper and lower terminals being open.

I preferably do not thread the interior of said offset locking portion 5. A coacting locking element is employed which is shown in the form of a tapered screw 6, which is threaded and desirably case hardened and which is proportioned in length and taper to fit in the portion 5 and coact with that portion of the periphery of the riser 1, adjacent thereto. When the band 3, is positioned, as shown, the screw 6 is turned into the tapered portion 5, and the case hardened threads cut into the threaded or smooth periphery of the riser 1 and the stock of the band 3, in a manner not only to form an effective anchorage but also to tighten the band 3 about the riser 1. The tapered form of these coacting anchoring elements affords a sufficient range to enable the band 3 to be firmly anchored irrespective of variations and inaccuracies of sizes.

I will next describe a novel feature of said screw 6, whereby the same serves as a protective element.

The upper end of the screw 6, is provided with a screw driver slot 7 adapted to receive the reduced end of a screw driver. This slot is formed between walls 8 and 9, of the stock of the screw, and I chamfer off wall 8, as shown at 10, and wall 9, as 110

shown at 11, so that at points diametrically opposite the center 12 there will be walls 13 and 14. It will be noted that these walls are not in opposite relation but in offset relation. Hence, looking at Fig. 8, it will be clear that when a screw driver is inserted and turned to the right, it will effectively abut walls 13 and 14, but when turned to the left, it will be ineffective to turn screw 6 because the portions 10 and 11 are reduced and merge into the stock of the screw at such a low elevation that they form no grip for the screw driver. Thus, it will now be seen that when the screw 6, has once been turned home, it is self locked against being surreptitiously removed. This novel form of head very interdependently coacts with the mutilations of the case hardened threads which the screw 6 cuts in the offset portion and on the riser, to prevent withdrawal of the screw. I therefore claim the screw in combination with the device as shown, and separately, as an article of manufacture.

25. I will next describe my improved closure band and the various functions it performs. Said closure band is indicated at 15, and it extends about more than one half of the circumference of the riser, in fact it is shown extending to nearly the complete circumference, the terminal ends 16 and 17, thereof, being bent outwardly to form hinge ears, as shown. This band 15 is preferably in spaced relation to band 3, and is provided with upper and lower inwardly extending flanges 18 and 19, respectively, terminating at 20, for engagement with the upper and lower edges, respectively, of band 3, to hold the bands in assembled relation. The inner edges of flanges 18 and 19, engage the periphery of the riser, when in place thereon, and thereby act to hold the band 15 in concentric relation therewith. Thus, it will be seen that the bands 3 and 15 are initially in loose relation with respect to each other and that they can be rotatively adjusted within the limit afforded by the terminal ends 20, of the flanges 18 and 19, on opposite sides of the offset 5. At a point diametrically opposite the ears 16 and 17 I provide the band 15 with an outstruck portion 21, which is adapted to form a keeper and coact with a closure locking device that will be presently described.

A feature of my invention is embodied in an over-arm structure which I will next describe in detail.

60 My improved over-arm is shown to be of U-shaped cross section having a bight or web 22 and side flanges 23. The length of said over-arm is such that it spans the diameter of the closure and riser extending from one diametrical point to another. 65 The over-arm web is terminated at 24 and

the flanges thereof are shaped to form hinge ears 25 and 26, which, in the present construction, overlap ears 16 and 17, and coact therewith by means of a hollow pintle 27, the ends 28 and 29 of which are over turned against ears 16 and 17 to form a hinged connection, as shown. At the opposite end of the arm, I mount a latch 30, which is pivoted on a rod 31 that is mounted in flanges 23. The latch end of the over-arm, as indicated at 32, is curved on a radius of which the axis of rod 31 is the center, so that the latch 30 can move into and out of a locking position. Said latch has a latch portion 33 which coacts with keeper 21, and is so disposed with respect to rod 31, that when in locking engagement, as shown in Fig. 2, any pull to lift the over-arm, would tend merely to increase instead of decreasing the locking action. Said latch is provided with an opening 34, adapted to receive the shackle of a padlock or other locking device for locking the latch against opening movement from the position shown in Fig. 2. A thumb grip 35, is available when it is desired to release latch 30, from the keeper 21. I provide a spring 36, mounted on the over-arm, and having a free end 37, engaging latch 30, to normally urge the latch into a locking position.

I will next describe my improved closure device and the functions it performs.

Said closure comprises an upper wall 38 having an upward crown 39 provided with a connection seat 40. I have shown connection means in the form of a rivet 41, having a head 42 engaging the over-arm and the shank passing downwardly through the over-arm and the wall 39, and the lower head 43 engaging the seat 40. It may be stated that the shank of said rivet passes sufficiently loosely through wall 39, to afford vent. A baffle 44, having a vent 45, forms a part of the closure and the margin 46, is turned downwardly, as shown. A gasket 47, is suitably fixed to the closure and is of a nature to yield when brought into engagement with the riser seat, in order to form a tight closure.

It is a feature of my invention to provide a spring normally acting to seat the closure and I will now describe the same.

As shown, a single length spring is employed, the bight 48 being looped about the rivet shaft 41 and bearing upon the wall or seat connection 40. The limbs 49 extend rearwardly below arm portion 22 and are wound about the hollow pintle 27, as shown, the free ends 50, being hooked under ears 16 and 17, as a means of anchorage.

In practice, this closing spring is of sufficient strength to snap the closure into a seated position with sufficient impact to cushion and compress the gasket 47 enough

to permit the latch 30 to snap into locking engagement with the keeper 21. Thus, in actual use, the spring closed cap is locked so that agitation of the contents splashing upwardly against the baffle 44, cannot open the closure. Further, the function of the closing spring has been performed, when it seats the closure, and thereafter, it has no further office to perform. It will be noted that when the gasket 47, has been compressed, as shown in Fig. 2, that the head 43 of the rivet is free from engagement with the connecting portion 40, thereby insuring a proper vent. As soon as the latch 30, is released, the closing spring will displace the closure and over-arm sufficiently to firmly seat the rivet head 43 against 40.

It is believed that the advantages and function of my invention will be fully understood from the foregoing description and while I have herein shown one specific form of my invention, I do not wish to be limited thereto except for such limitations as the claims may import.

25 I claim:

1. A tank closure structure for tanks having a riser comprising, an anchoring adapter band adapted to outwardly telescope the riser and having a conical offset portion, a case hardened conical screw adapted to be turned into said offset portion and into engagement with the periphery of said riser to lock said band on the latter, and a closure structure for said riser.

35 2. In a closure structure for tanks having a riser comprising, an anchoring adapter band adapted to outwardly telescope the riser and having an offset portion, a case hardened screw adapted to be turned into said offset portion to coact with the latter and a portion of the periphery of said riser to lock said band on said riser, a closure structure for said riser, and means for movably mounting said closure structure on said band.

45 3. In a closure structure for tanks having a riser, a closure device having a lower perforated baffle for venting the tank's contents, said closure having a top wall, an over-arm, means connecting said over-arm with said top wall, and a device for locking said over-arm to seat said closure device under pressure sufficiently to loosen said means and afford vent through said top wall.

55 4. In a closure structure for a tank riser, an adapter anchoring band adapted to be fixed to a riser, a closure band in circumfer-

ential spaced relation to said anchoring band and having upper and lower inturned flanges engaging the upper and lower edges, respectively, of said anchoring band to hold said bands in assembled relation and the inner edges of said flanges being adapted for peripheral engagement with the riser to maintain said bands in concentric relation, and a closure for said riser hinged to said closure band.

5. In a closure structure for a tank riser, an adapter anchoring band adapted to be fixed to the riser, a closure band in circumferential spaced relation to said anchoring band and having flanged engagement with the latter to hold said bands in assembled relation but normally free for rotative adjustment and the ends of said closure band projecting in parallel relation to form hinge ears, a closure for said riser, an over-arm having ears disposed abreast of said closure ears and pivoted thereto, means for connecting said closure to said over-arm, and a spring actuated latch on said over-arm for locking engagement with said closure band.

6. In a closure structure for a tank riser, a band structure adapted to be fixed to the riser and having a keeper, a closure for said riser, an over-arm hinged at one diametrical point of said band structure from said keeper, and having a spring actuated latch for engagement with said keeper, a gasket between said closure and riser, and a spring normally acting to close or seat said closure with sufficient impact to compress said gasket enough to lock said latch with said keeper.

7. In a closure structure for a tank riser, a band structure adapted to be fixed to the riser and having a keeper, a closure for the riser, an over-arm hinged to said band structure and having a latch for coaction with said keeper, and a spring for closing said closure with sufficient impact to engage said latch with said keeper.

8. A tank closure structure for a tank riser including, an anchoring band surrounding the riser and having a conical offset portion, and a case hardened conical screw adapted to be turned into said portion to form a threaded connection therewith and with a peripheral portion of said riser to lock said band on the riser.

In testimony that I claim the foregoing as my own, I hereby affix my signature.

LOU C. ELLER.
